SWITCH

Hugo Gross, Brooklyn, and Jack A. Potenza,
Ford Warthworth, N. Y.

Application May 13, 1939, Serial No. 273,382

9 Claims. (Cl. 200—116)

This invention relates to electric switches in general, and particularly to what may be termed automatic cut-out or safety switches.

The prime object of this invention is to provide a temperature-responsive electric switch, which will automatically cut out or break an electric circuit controlled by the switch, when the circuit is either shorted or becomes overloaded, and due to which short or overload the resistance in the circuit will heat the switch mechanism sufficiently to automatically operate the latter to its circuit breaking position.

Another object of the present invention is to provide an automatically operating, temperature-controlled safety or cut-out switch, which is intended to entirely replace heretofore employed safety fuses in electric circuits, and wherein external, manually operable means are provided for actuating the switch to either a circuit closing or circuit breaking position, and which switch will automatically assume a circuit breaking position when a short or an overload occurs in the circuit, and which switch cannot be manually brought to its circuit closing position until such short or overload is remedied.

Still another object of this invention is to provide such automatic safety switch with a sparkless and vaporproof circuit closing and circuit breaking element, which is adapted to operate independently from the manual switch actuating means, and which element is controlled by a heat responsive instrumentality designed to release said element to a circuit breaking position when the circuit is either shorted or over-loaded.

A still other object of this invention is to provide in such switch suitable indicating means, adapted to show the position of such element, irrespective of the position of the manual switch operating means.

A further object of the present invention is to provide such switch with a removable cover enclosing the entire switch mechanism, and which cover may be sealed against unauthorized removal.

Another object of this invention is the employment in such switch of a mercury controlled switch element, wherein a hermetically sealed, electro-conductive casing forms the mercury container and serves as one of the contact members of the element, whereas its other contact member consists of an insulated rod or pin extending into one end of the casing, and wherein the mercury serves as conductor between the casing and said pin, when the element is in its circuit closing position, and wherein the casing

is filled with an oxidation, spark and vapor preventing agent.

The foregoing and still further important objects of the present invention will become more fully apparent from the ensuing description, in conjunction with the accompanying drawing, showing one of the presently preferred forms of this disclosure, and wherein

Fig. 1 is a top view of our switch, partially in cross section, taken on lines 1—1 of Fig. 2.

Fig. 2 is a front elevation thereof, partially in cross section, taken on lines 2—2 of Fig. 1, with the switch operating mechanism, as well as with the circuit closing and breaking element in inoperative or breaking position.

Fig. 3 is an end view, of the switch, partially in cross section, taken on lines 3—3 of Fig. 2.

Fig. 4 is another end view of the switch, partially in cross section, taken on lines 4—4 of Fig. 2.

Fig. 5 is a similar view to that of Fig. 2, with the switch operating mechanism and the circuit breaker in operative, circuit closing position.

Fig. 6 is a similar view to that of Fig. 5, wherein the switch operating mechanism is in operative position, whereas the circuit breaker is in released, circuit breaking position.

Fig. 7 is a partial cross sectional detail top view, taken on lines 7—7 of Fig. 2.

Fig. 8 is a longitudinal cross sectional view taken on lines 8—8 of Fig. 2, and showing the adjustable end support for the circuit making and breaking element.

Fig. 9 is a perspective detail view of a portion of the switch operating mechanism.

Fig. 10 is a front elevation, and

Fig. 11 is a side elevation of the switch, enclosed within its sealed housing.

Fig. 12 is a perspective view of a conductive bracket for the circuit breaker element employed in my device, which provides a pivotal connection for the element.

Figure 13 is a diagram showing a movement for operating the switch.

Referring now more specifically to the figures, numeral 10 represents the dielectric base or back panel of the switch in which are permanently mounted upper and lower leads or conductors 11 and 12. Fitting over panel 10 is a removable, but sealable switch housing 13 which is preferably provided at its upper surface with an opening 14, the purpose of which will be apparent later.

Secured to panel 10 and electrically connected with upper lead 11 by a screw or similar means

15, is a conductive bracket or support 16, in the form of an inverted channel. Pivotedly secured to support 16 at 17 and 18 (see Figs. 1, 4, and 7) is a dielectric frame 19, in the shape of a long-flanged channel or fork, within which latter is operatively mounted a circuit closing and breaking element 20 in the form of a hermetically sealed, metallic mercury contact tube. The latter is pivotally lodged at 21 and 22 within frame 19 (see Figs. 4 and 7) in such a manner that both frame 19 as well as element 20 may independently swing about their respective pivotal points, which latter are preferably aligned with one another.

Secured to support 16 at 23 is a spring 24, the free end of which bears against mercury tube 20 and normally urges it into a downward, circuit breaking position. Within pivotal frame 19 are secured to the interior faces of the frame legs, resilient, conductive blades 25 and 26, clearly seen in Figs. 4, 7 and 9. At the end of the frame legs these blades are held in place by conductive blocks 27 and 28, which serve as attaching means for bimetallic, heat responsive semi-loops 29 and 30, joined together by a metallic bridge 31. At the center of bridge 31 there is provided an adjustable support 32, which is pivoted at 33 (see Fig. 21). The upper end of support 32 is urged towards mercury tube 20 by spring 34. The position of the support may be adjusted by screw 35 engaging its lower end. Support 32 is intended to normally form a rest for an insulated pin 36, extending from an insulating plug 37, which latter hermetically seals one end of tube 20. The end of pin 36 is cut at an angle to facilitate its cooperation with support 32.

The other end of the tube is sealed by another insulating plug 38, in which is secured a threaded contact rod or pin 39. The inner ends of both plugs 37 and 38 are held within suitable recesses 40 and 41, provided in the metal tube, while the ends of the tube are drawn in and against corresponding recessed portions 42 and 43 provided in the plugs.

Plug 38 is enclosed by insulating cap 44, which is provided with an aperture for accommodating threaded contact pin 39. Cap 44 is held in its intended position by nut 45, which engages the pin. Nut 45 also secures the end lug of flexible conductor 46 to pin 39. This conductor is electrically connected by a screw or other means 47, through panel or base 10, to conductor 12.

Tube 20 contains a small quantity of mercury, indicated at 48, which is adapted to either establish contact between the metallic tube body and pin 39, or disrupt that contact, depending upon the position of the tube.

From Fig. 7 it will be seen that switch operating frame 19 and the mercury tube are pivoted in such a way that their pivotal points are aligned with one another. Pivotal point 21 of the tube consists of two elements, a screw pin 49 and a bracket 50, the latter being shown in detail in Fig. 12. This bracket is slipped through a suitable cut made into cap 44. The larger perforated end 50' of the bracket engages tube 20 and electrically connects it to resilient blade 26, by way of pin 49, which passes through the smaller apertured end 50" of the bracket. Pin or bolt 49 is lodged within an insulating member 51 which passes through a suitable aperture provided in the lower portion of support 16.

The conductive instrumentalities of the switch 75

mechanism form the following electric connection: From line terminal 12 current passes by way of screw 47 and flexible conductor 46 to contact pin 39 within the tube. When the latter is in "off" position, all other switch parts are disconnected from the line. When switch tube 20 is in its "on" position, shown in Fig. 5, mercury 48 connects pin 39 with the conductive body of tube 20, from which latter current is conveyed through bracket 50, swivel connection 21, formed by pin 49, to resilient blade 26, from there to block 28, from the block to resilient bimetallic element 30, over bridge 31 to bimetallic element 29, to block 27, and through resilient blade 25 and pin 18 to support 16 which is connected at 15 to terminal bar 11. In this manner current is conveyed from "hot" terminal bar 12 to terminal bar 11.

Tube 20 is hermetically sealed and contains, 20 besides the mercury, certain agents, such as hydrogen and nitrogen, or any other medium which will prevent the formation of sparks, the oxidation of the contact elements, i. e. tube 20 and contact pin 39, while at the same time eliminating the formation of vapors usually due to sparking.

The actuating mechanism of the switch consists of the manually operable frame 19, to the outer leg of which is secured a switch manipulating pin 52 (see Fig. 1). This pin is actuated by any suitable arrangement, such as a toggle mechanism, manually operable through tumbler knob 53, seen at Figs. 10 and 11. Any effective mechanism operatively connecting tumbler knob 53 with pin 52 for actuating the movable parts of the switch may be employed, and it is our intention that such mechanism is to be considered included as an essential part of the present disclosure.

40 A proposed movement for operating frame 19 is illustrated in Figure 13, wherein the interior portion of tumbler knob 53 and pin 52 are shown in sections, while the rest of the mechanism is indicated as if the front wall of the cover would be transparent. The entire mechanism is intended to be arranged adjacent to the interior surface of the front wall of cover 13. The movement consists of a bell crank 63, engaged by the rear portion of tumbler knob 53. The longer leg 50 of the bell crank actuates a slide 64. The slide is provided with a recess engaging a pin 65, extending from pivotal lever 66, the pivotal point of which latter coincides with the pivotal point of frame 19 and of the mercury tube 20. In 55 the swinging end of lever 66 is provided an elongated slot which is adapted to engage pin 52, by means of which the frame may be either snapped upwards or downwards. This snapping motion is facilitated by an over-center, spring-induced pivotal connection 67.

60 Pivotedly mounted at the upper right-hand corner of the switch upon rod 54 is an indicator device 55, visible through aperture 14 provided in housing 13. This indicator device has a tell-tale extension with the readings "on" and "off" marked thereon and is normally held in the "off" position by coil spring 56 (see Figs. 3 and 4).

65 Indicator 55 has a depending lip 57, by means of which it is moved to its "on" position through plug 37 of tube 20, when the latter becomes elevated in the manner shown in Fig. 5. A downwardly extending arm 58 forms the stop means for the indicator when in its "off" position, at which its lower end comes in contact with the lower sealing pin 59 of the switch.

The switch is equipped with at least two sealing pins, the lower already mentioned, and an upper sealing pin 60. These sealing pins are secured in base 10 and are adapted to pass through the front wall of cover 13. The protruding ends of the pins are perforated for the purpose of enabling the attachment therethrough of seals 61, which are provided for the purpose of preventing the removal of the switch cover and unauthorized tampering with the switch mechanism, especially at the time when the circuit breaking element automatically moves to the "off" position, due to a short or an overload occurring in the circuit served by the switch.

Operation

The switch is intended to be used in its horizontal position, as shown in Figs. 2, 5 and 6. The instrumentalities of the switch mechanism, constituting electric conductors between the different parts of the switch within the switch housing, are to be especially noted, primarily resilient blades 25 and 26 which are intended through their resiliency to provide positive electric connections between support 16, through bracket 50, and tube 20.

The device is operated like any other switch. When tumbler knob 53 is manually actuated so that frame 18 is swung upwards, the latter, together with circuit breaker 20, is thrown to the position indicated in Fig. 5. At this position, bimetallic loop elements 28 and 30 are in their normal relation to tube 20, in that insulated pin 36 rests with its tapered end upon support 32 of bridge 31. This support may be adjusted so that the slightest outward deflection of bimetallic elements 28 and 30 from their normal position, will release pin 36. Such adjustment is facilitated by adjusting screw 35 against the tension of spring 34, which latter normally urges the upper end of support 32 towards the tube 20.

When tube 20 is in its uppermost position, end lip 57 of the indicator is pushed upwards, thereby rendering designation "on" visible through opening 14. In this position the body of tube 20 is connected through mercury 48 with contact pin 38, and current flows from conductor 11 through the circuit breaker to conductor 12. In the event of an overload or of a short occurring in the circuit, the resistance to the path of the current through the switch instrumentalities will raise their temperature above normal. A sufficient amount of heat, though it may be relatively low, will cause bimetallic loop elements 28 and 30 to move away from tube 20 and carry with them bridge 31. In consequence of this movement, support 32 will release pin 36.

Spring 24, mounted on support 16, normally urges tube 20 to its downward, circuit breaking position, indicated in Figs. 2 and 6. The moment pin 36 is released from its support 32, the action of spring 24 will swing tube 20 to its lowermost position until it comes to rest upon stop 62, provided in the switch housing (see Figs. 1, 2, 5 and 6). At the same moment, indicator 55 will be swung to its "off" position by spring 56, and will stop in its swinging movement when the lower end of its arm 58 engages lower sealing pin 60.

When switch element 20 is in its downward position, the mercury will flow from contact pin 38 against dielectric end plug 37. Thus the current is interrupted, in consequence of which the bimetallic loops 28 and 30 will assume their normal position.

In order to again close the circuit, tumbler knob 53 must be operated first so that frame 18, which remained in its upward position during the automatic downward movement of tube 20, is brought into operative engagement with the tube. Such operative engagement is established by pin support 32 gliding over the inclined face of pin 36 until the lower end of the pin is reseated upon the upper edge of the support. Then the switch mechanism is brought to its upward position, shown in Fig. 5, by the second movement of tumbler knob 53.

Until the overload or short in the circuit is remedied, tube 20 will be again released and will open the circuit in the manner stated before, unless it is forcibly held in its up-swing position. This is made possible only by the removal of cover 13 from the base. Such removal is prevented by seals 61, which have to be broken in order to free housing 13. It is the intention of this invention to prevent tampering with the switch by unauthorized persons, for which reason the housing is preferably sealed in place.

It is to be noted that both the switch actuating mechanism, consisting principally of oscillating frame 18 and the oscillating circuit breaking element 20 may move independently relative of one another. The compactness, simplicity and low cost of the switch make possible the replacement of heretofore used, existing switches which do not provide the safety and advantages of the present invention. The automatic release of our circuit breaker, caused through shorts or overloads eliminates the use of safety fuses heretofore employed in electric circuits.

While the foregoing description deals with a specific form of our invention, it is quite obvious that changes, improvements, and simplifications may be readily provided in our switch construction, and we, therefore, reserve for ourselves the right to make such changes, improvements and simplifications therein, without departing from the broad scope of our invention, as defined in the annexed claims.

We claim:

1. In an electric safety switch intended to replace safety fuses in an electric circuit, a self-contained, pivotally mounted circuit breaker, a manually operable, pivotally mounted dielectric frame for accommodating therewithin and for actuating said circuit breaker and capable of moving independently in respect with the latter, the pivotal points of said circuit breaker and of said frame coinciding with one another, a heat responsive, electro-conductive end support for the breaker provided at the free end of said frame for automatically releasing said breaker to its circuit opening position when said end support becomes subjected to resistance heat due to shorting of or an over-load in the circuit.

2. In an electric safety switch, as set forth in claim 1, and wherein said circuit breaker comprises an electro-conductive mercury tube, provided with dielectric seals at both ends and being filled with an oxidation and spark-preventing agent.

3. In an electric safety switch, as set forth in claim 1, said circuit breaker consisting of an electro-conductive tube, sealed at both ends by dielectric closures, a contact element projecting into the tube through one of the closures, an insulated rest pin extending from the other closure at the free end of the tube and cooperating with said heat responsive support, mercury in said tube for establishing contact between the tube

body and said contact element, and an oxidation and spark-eliminating agent hermetically sealed within said tube.

4. In an automatic cut-out switch, a dielectric base, at least two electric conductors issuing from the base, a cover removably associated therewith, means for securing the cover to the base against unauthorized removal, a conductive bracket extending from the base and connected with one of the conductors, an oscillating frame mounted in the bracket, a sparkless and vapor proof circuit breaker pivotally secured within the frame and capable of moving independently relative thereto, heat responsive, adjustable means for normally supporting the free end of the breaker, associated with free end of the frame, resilient electro-conductive instrumentalities arranged within said frame and establishing electric contact from said bracket over said heat responsive supporting means to one of the contact members of the breaker, the other contact member of the breaker being connected with the other electric conductor of the base, and a position indicator for the breaker observable from without the cover.

5. In an automatic cut-out switch, as set forth in claim 4, said circuit breaker comprising a hermetically sealed metallic tube, constituting the one contact member of the breaker, said tube being filled with an agent for preventing oxidation, spark and vapor formation, dielectric seals closing the tube ends, mercury within the tube, the other contact member of the breaker consisting of a threaded pin passing through one end seal of the tube at the latter's pivotal end, and resilient means normally urging the tube into contact breaking position.

6. In an automatic cut-out switch, as set forth in claim 4, said circuit breaker comprising a hermetically sealed metallic tube, constituting the one contact member of the breaker, said tube being filled with an agent for preventing oxidation, spark and vapor formation, dielectric seals closing the tube ends, mercury within the tube, the other contact member of the breaker consisting of a threaded pin passing through one end seal of the tube at the latter's pivotal end, and resilient means normally urging the tube into contact breaking position, one of the pivotal points of said tube comprising a bracket formation extending from one of the resilient, conductive instrumentalities in the frame towards and into contact engagement with the tube.

7. In an automatic cut-out switch, as set forth in claim 4, said circuit breaker comprising a hermetically sealed metallic tube, constituting

the one contact member of the breaker, said tube being filled with an agent for preventing oxidation, spark and vapor formation, dielectric seals closing the tube ends, mercury within the tube, the other contact member of the breaker consisting of a threaded pin passing through one end seal of the tube at the latter's pivotal end, and resilient means normally urging the tube into contact breaking position, one of the pivotal points of said tube comprising a bracket formation extending from one of the resilient, conductive instrumentalities in the frame towards and into contact engagement with the tube, a dielectric end cap covering said dielectric seal near the pivotal end of the tube, said bracket formation passing through the end cap, said threaded pin extending through said end cap, means for forcing the end cap against said bracket formation and the latter into contact with the tube, and a flexible electric conductor connecting said pin with said other conductor of the base.

8. In an electric safety switch, an oscillating fork-like dielectric frame pivoted at one end and free to swing at its other end, said other end constituting a pair of free legs, a mercury tube circuit breaker pivotally mounted within, but capable of independent movement in respect to the frame, the pivotal axis of the tube and of the frame coinciding, an adjustable rest for the free end of the tube provided between and at the free end of the frame legs, heat responsive elements extending from the leg ends and supporting said rest, means secured to the frame for normally urging said tube against said rest, manually operable means for snapping the free end of the frame, and with it the tube, to either a circuit making or a circuit breaking portion, said supporting elements being adapted to shift said rest out of engagement with the free end of the tube and thus automatically release the latter to its circuit breaking position when the circuit becomes shorted or overloaded.

9. In an electric safety switch, as set forth in claim 8, and wherein said mercury tube circuit breaker consists of a hollow, electro-conductive body having dielectric end seals, a conductive contact member extending through one of the seals into the body, and means at the end of the other seal for cooperating with said rest of the frame.

HUGO GROSS.
